Primary Examiner — Eric L Goodman*Assistant Examiner* — Amy C Wierenga(74) *Attorney, Agent, or Firm* — The Webb Law Firm(57) **CLAIM**

The ornamental design for a seal member for a pressure vessel, as shown and described.

DESCRIPTION

FIG. 1 is a top view of a seal member for a pressure vessel showing our new design;

FIG. 2 is a front elevation view thereof;

FIG. 3 is a right side elevation view thereof;

FIG. 4 is a cross-sectional view thereof taken along lines 4-4 shown in FIG. 1;

FIG. 5 is an enlarged cross-sectional view of a portion thereof defined by area 5-5 shown in FIG. 1;

FIG. 6 is an enlarged cross-sectional view of a portion thereof in a condition of use; and,

FIG. 7 is a perspective view thereof.

The bottom, rear elevation, and left side elevation views of the seal member for a pressure vessel are omitted as they are identical in appearance to the top, front elevation, and right side elevation views, respectively.

The dot dash broken line shown in FIG. 5 indicates cutoff boundaries for the enlarged detailed portion view and forms no part of the claim.

The evenly dashed lines in FIG. 6 depict environmental subject matter that forms no part of the claim.
